UNITED STATES PATENT OFFICE

115,915

DESIGN FOR A PANTS HANGER

Charles Eric Daniels, Los Angeles, Calif.

Application April 15, 1939, Serial No. 84,312

Term of patent 7 years

To all whom it may concern:

Be it known that I, Charles Eric Daniels, a citizen of the United States, residing at Los Angeles, in the county of Los Angeles, State of California, have invented a new, original, and ornamental Design for a Pants Hanger, of which the following is a specification, reference being had to the accompanying drawing, forming a part thereof.

I claim:

The ornamental design for a pants hanger, as shown.

CHARLES ERIC DANIELS.
